Oscar M. Clink, 1446 W. Slauson Ave.,
Los Angeles, Calif. 90047

Filed June 5, 1968, Ser. No. 12,224

Term of patent 7 years

Int. Cl. D22—07

U.S. Cl. D22—30

FIG. 1 is a view in elevation of one side of the trolling sinker showing the new design with which the opposite side corresponds;

FIG. 2 is an elevational view of the trolling sinker as seen in the direction of the arrow 2 in FIG. 1; and

FIG. 3 is an end view as seen in the direction of the arrow 3 in FIG. 2;

FIG. 4 is a view in cross section and plan taken on the line 4—4 of FIG. 1.

The broken lines are for illustrative purposes only. The parallel lines in the recesses on opposite sides of the item indicate the color red.

I claim:

The ornamental design for a trolling sinker, substantially as shown and described.
